COMBINED WINDOW OPERATOR AND LOCK

John B. Flynn, Detroit, Mich., assignor to Ternstedt Manufacturing Company, Detroit, Mich., a corporation of Michigan

Application April 13, 1936, Serial No. 74,067

10 Claims. (Cl. 268—119)

This invention relates to a combined window operator and lock.

The object of this invention is to produce a combined window operator and lock which is simple in structure, easy to operate and positive in operation.

In the drawings:

Fig. 1 is a fragmentary view showing an automobile door window assembly with a swinging panel operated and locked by the combined window operator and lock.

Fig. 2 is a vertical section through the door showing the attachment of the combined operator and lock to the swinging window glass.

Fig. 3 is a front elevation partly in section of the combined operator and lock.

Fig. 4 is a vertical section through the combined operator and lock showing the position of the driving worm when the locking bolt is retracted.

Fig. 5 is a view similar to Fig. 4 showing the position of the worm when the swinging window glass panel is closed and locked.

Fig. 6 is a front elevation of a modified form of the combined window operator and lock.

Fig. 7 is a horizontal section through the modified form of combined window operator and lock shown in Fig. 6 showing the position of the driving worm when the window is unlocked.

Fig. 8 is a view similar to Fig. 7 showing the position of the worm when the window is locked.

Fig. 9 is a section along the line 9—9 of Fig. 7.

Fig. 10 is a horizontal section through a second modification of the principal form of the invention showing in the full lines the position of the parts when the window is unlocked, and in the dotted lines the position of the parts when the window is locked.

Fig. 11 is a view corresponding to Fig. 10 showing the position of the parts when the window is open.

Fig. 12 is a section along the line 12—12 of Fig. 10.

Referring more particularly to the drawings, there is shown an automobile door 1 having a no draft window comprising a sliding panel 2 and a swinging panel 3. The swinging panel is mounted in a frame 5 which is fixed to, and supported upon, a vertical shaft 4. The panel 3 is thus arranged to swing in the well-known manner about a vertical axis between its front and rear edges to open and closed position. Although this combined window operator and lock is shown with a swinging panel, it is understood that it is equally adaptable for use with sliding

and other types of closures and window glass panels.

The window operator comprises a casing 6 which may be die cast or otherwise formed. The casing 6 is fixed to and supported upon a plate 7. The plate 7 is welded or otherwise fixed to the channel 8 for the weatherstrip which seals the edge of the swinging glass panel frame 5. Either or both the weatherstrip channel 8 and the support plate 7 are fixed in the window well by welding, riveting, or otherwise securing the same to the belt rail. A worm gear 9 is journalled as at 10 and 11 in the casing 6 to rotate about a vertical axis. The upper end of the worm gear 9 has a socket 12 for the lower end of the shaft 4. A bolt 13 is passed through the socket 12 and shaft 4 to tie the two together.

The worm gear 9 is driven by a worm 13 fixed on a shaft 14. The shaft 14 is journalled in the casing 6 as at 15 and in the plate 7 as at 16. The inner end of the shaft 14 is provided with the usual crank handle 17 for turning the same. The shaft 14 is also arranged so that it can slide axially in the bearings 15 and 16. A coil spring 18 is mounted between the bearing 15 and the worm 13. Coil spring 18 is sufficiently strong so that during the normal closing and opening of the window panel 3 the shaft 14 will not slide axially but will remain in the position shown in Fig. 4 and transmit the driving torque to the worm gear 9. However, when the window reaches closed position further turning of the worm 13 by the crank handle 17 will cause the now stationary worm gear to cam the worm 13 outwardly and thereby shift the spindle 14 axially to compress the coil spring 18 (Fig. 5). This shifting of the spindle 14 and worm 13 is utilized to latch the swinging panel 3 in closed position.

To this end a lever 19 is journalled in the casing 6. One end 20 of the lever 19 is positioned beneath the spindle 14 and immediately behind the worm 13. The other end 21 of the lever is connected by a link 22 with a bell crank lever 23 pivotally mounted as at 24 on the plate 7. The bell crank 23 has a pivotal connection as at 25 with the lower end of the vertically sliding bolt 26. The bolt 26 is guided in a sleeve 27 through an opening in the flange 28 of the plate 7 and through an opening in the base of the weatherstrip channel 8. The window frame 5 is provided with an opening 29 which serves as a keeper into which the bolt 26 is projected to lock the window panel 3 in closed position. The bolt 26 is provided with a shoulder 30. A coil spring 31 is mounted between the shoulder 30

30 and the flange 28 of the plate 7 and normally tends to urge the bolt 26 to retracted position.

The operation of this device is as follows: When the window panel 3 is open or has just reached closed position the various parts of the regulator and bolt are in the position shown in Figs. 3 and 4. As soon as the window panel 3 in frame 5 reaches closed position further turning of the handle 17 and worm 13 is resisted by the now stationary worm gear 9 owing to the inability of the window panel 3 to swing beyond closed position. Since the worm gear 9 cannot turn further, it acts as a cam upon further turning of the worm 13 to cam the worm 13 from the position shown in Fig. 4 to the position shown in Fig. 5. Since the worm 13 is fixed on the shaft 14, the shaft shifts axially to the right as viewed in Fig. 2, further compressing the spring 18, Fig. 5. As the shaft 14 and worm 20 shift axially the worm engages the end 20 of the lever 19, swinging the same counter-clockwise, Figs. 3 and 4, which, through the link 22 swings the bell crank 23 counter-clockwise, thus projecting the bolt 26 into the keeper opening 27 and compressing coil spring 31. This locks the window panel 3 in closed position. If crank 17 is now turned to open the window, the initial turning movement of the crank 17 will cause the worm 13 to be cammed outwardly by the worm gear 9 until the worm 13 abuts the plate 7 as at 52, thus permitting the coil spring 31 to retract the bolt 26 from the opening 29 and acting through the bell crank 23 and link 22 swing the lever 19 clockwise so that the end 20 is held against the shoulder of the worm 13. After the worm reaches normal position abutting against the plate 7 as at 52, shown in Fig. 4, further turning of the worm will rotate the worm gear to swing open the window panel 3.

40 A modified form of this combined window operator and lock is shown in Figs. 5 through 9. In this form of the invention the worm gear 9 is driven by the worm 40 which is splined upon the shaft 41. The shaft 41 is journalled in the casing 6 in the same fashion as the shaft 14 and also turned by the usual crank handle 17. A lever 42 is pivotally mounted upon the base of the casing 6. One end of the lever is pivotally connected to the link 22 as at 43 and the other end of the lever has a swivel connection as at 44 with a plate 45. The plate 45 has an opening 46 through which the reduced end 47 of the shaft 41 is threaded so that the plate 45 can shift lengthwise along the reduced end 47 of the shaft 41. A coil spring 48 is threaded over the shaft 41 and mounted between the plate 45 and the wall of the casing 6 so that the coil spring normally urges and holds the plate 45 and worm 40 in the position shown in Figs. 7 and 9.

50 In this form of the invention the spring 48 exerts sufficient tension so that during the normal closing and opening of the swinging window 3 the driving torque will be transmitted from the worm to the worm gear to open and close the window. As soon as the swinging window panel reaches closed position the worm gear 9 cannot turn further. Further turning of the worm 40 causes the worm gear to act as a cam and cams the worm 40 axially along the shaft 41 from the position shown in Fig. 9 to that shown in Fig. 8, thereby compressing the spring 48 and at the same time shifting the plate member 45 along the reduced portion 47 of the shaft from the position shown in Fig. 9 to that shown in Fig. 8. This movement of the plate 45 causes the lever 42

to swing counter-clockwise and thereby through the link 22 and bell crank lever 23, project the bolt 26 into the keeper opening 29 in the window frame to lock the swinging window in closed position. When the crank handle 17 is turned to open the window the initial turning movement of the crank handle will now cause the worm gear 9 to cam the worm 40 outwardly, thus permitting the coil spring 48 to expand and force the plate 45 outwardly or toward the right from the position shown in Fig. 8 to that shown in Fig. 9 so that the plate 45 follows the worm 40. This outward movement of the plate 45 is transmitted through the lever 42, link 22, lever 23, to the bolt 26 which is retracted from the keeper opening 29 to the full line position shown in Fig. 6. As soon as the worm 40 reaches the end of its outward travel, it abuts against the plate 7 as at 50. Further turning of the worm 40 will turn the worm gear 9 and open the swinging window.

A second modified form of the invention is shown in Figs. 10, 11 and 12. In this form the window glass frame 5 is bolted by the same type of link 22, bell crank 23 and bolt 26 as shown in the principal above described form of the invention. In this second modified form of the invention the worm 60 is fixed upon, or integrally formed with, the shaft 61 which is turned by the usual crank handle 17. The shaft 61 is journalled in the casing 6 as at 62 and 63. The support shaft 4 for the swinging window glass 3 has fixed on its lower end the worm gear 64 provided with the usual gear teeth 65. The lower end of the shaft 4 and worm gear 64 are provided with a bore 66 in which is journalled the shaft 67. The worm gear is also provided with an arcuate opening 68 extending outwardly from the bore 66 to the outer surface of the gear.

A swinging gear tooth 69 is keyed to the shaft 67 by the key 70 and swingably mounted in the opening 68. This swinging gear tooth 69 retains the shaft 67 in the bore 66. A crank arm 71, provided with a square opening, is secured on the square end 72 of the shaft 67 to swing with the shaft and acts through link 22 and bell crank 23 to project and retract the bolt 26.

In the operation of this modified form the position of the worm gear 64 when the window is fully open is shown in Fig. 11. If the crank handle is now turned to close the window, the worm gear 64 will turn in a counter-clockwise direction and the swinging window will reach closed position when the worm gear 64 reaches the position shown in Fig. 10. At this time it will be noted that the swinging gear tooth 69 has just reached the position where it meshes with the worm 60 and the gear teeth 65 of the worm gear 64 have just passed out of mesh with the worm 60. Therefore further turning of the worm 60 in the same direction will cause the gear tooth 69 to travel along the worm in a counter-clockwise direction from the full line position shown in Fig. 10 to the dotted line position, thus swinging the shaft 67 and arm 71 counter-clockwise from the full line position to the dotted line position. As the arm 71 swings from the full to the dotted line position, the link 22 is moved to the right as viewed in Fig. 3, thus throwing the bolt 23 into the keeper opening 29 to lock the swinging window. If the crank handle is now turned in the opposite direction to open the swinging window, the initial turning movement of the worm 60 will cam the gear tooth 69 from the dotted line position, Fig. 10, to the full line position 75

thereby through the shaft 67, arm 71 and link 22 retracting the bolt 26 from the keeper opening 29 in the frame 5. As soon as the gear tooth 69 in its clockwise rotation reaches the full line 5 position, Fig. 10, it abuts the side wall 75 of the opening 68, thus transmitting the driving torque to the driven worm gear and swinging the worm gear 64 in a clockwise direction so that the worm gear teeth at the opposite end of the opening 68 10 are meshed with the worm 60 whereupon further turning of the worm 60 will rotate the worm gear and swing the window to open position.

I claim:

1. In a window assembly comprising a window opening and a window panel arranged to be moved to closed position, in combination an operator for moving the window to closed position, a lock for locking the window panel in closed position, the said window panel operator comprising rotatable driving worm and driven worm gear members, operative connections between the rotatable driven worm gear member and the window panel whereby the driven member is stationary when the window panel reaches closed position, a shiftable member operative only when the window panel is closed and the driven worm gear member stationary, operative connections between the shiftable member and the lock, the said shiftable member being operatively connected 20 with the rotatable driving worm member whereby only after the window panel reaches closed position and the driven worm gear member is stationary further rotation of the driving worm member shifts the shiftable member and operative connections to throw the lock into interengagement with the closed window panel.

2. In a window assembly comprising a window opening and a window panel having a frame arranged to be moved to closed position, in combination an operator for moving the window to closed position, an opening in the frame serving as a keeper, a bolt for interengaging the keeper when the window panel is closed, the said operator comprising rotatable driving worm and driven worm gear members, operative connections between the rotatable driven worm gear member and the window panel whereby the driven member is stationary when the window panel reaches closed position, a shiftable member operative only when the window panel is closed and the driven worm gear member stationary, operative connections between the shiftable member and the bolt, the said shiftable member being operatively connected with the rotatable driving worm member whereby only after the window panel reaches closed position and the driven worm gear member is stationary further rotation of the driving worm member shifts the shiftable member and operative connections to throw the bolt into interengagement with the keeper carried by the window panel.

3. In a window assembly comprising a window opening and a window panel arranged to be moved to open and closed positions, the combination of a window operator including rotatable driving and driven members in dental engagement, a lock for interengaging the window panel when closed, one of the said driving and driven members being arranged to shift only upon further actuation of the operator after the window panel is closed, and operative connections between the shiftable member and the lock operated by the shifting of the shiftable member to throw the lock into interengagement with the window panel to lock the same.

4. In a window assembly comprising a window opening and a window panel arranged to be moved to open and closed positions, the combination of a window operator for the said window panel including rotatable driving and driven members, a lock for interengaging the window panel when closed, operative connections between the driven member and the window panel whereby the driven member is stationary when the window panel reaches closed position, the said driving member being axially shiftable along its axis of rotation when the driven member is stationary, and operative connections between the lock and the shiftable driving member for throwing the lock into interengagement with the window panel when the panel is closed.

5. In a window assembly comprising a window opening and a swinging window panel arranged to be moved to open and closed positions, the combination of a window operator comprising a driving worm and a worm gear, a lock for interengaging the window panel when closed, a shaft for operatively connecting the worm gear to the swinging window, a support for the driving worm, the said driving worm being axially shiftable along its support, operative connections between the lock and the shiftable worm operated by the shifting of the worm when the window panel is closed to throw the lock into locking interengagement with the closed window panel.

6. In a window assembly comprising a window opening and a swinging window panel arranged to be moved to open and closed positions, the combination of a window operator including a worm and a worm gear, operative connections between the worm gear and the swinging window whereby the worm gear is stationary when the swinging window is in closed position, a support for the said worm, the said worm being axially shiftable on the said support, resilient means for holding the worm against shifting and in driving relation with the said worm gear during the closing of the window and yielding to permit axial shifting of the worm along its support upon further turning of the worm when the window panel is closed, operative connections between the worm and the lock actuated in the shifting of the worm for throwing the lock into interengagement with the window panel when closed.

7. In a window assembly comprising a window opening and a swinging window panel arranged to be moved to open and closed positions, the combination of a window operator including a worm and a worm gear, operative connections between the worm gear and the swinging window whereby the worm gear is stationary when the swinging window is in closed position, a rotatable shaft, the worm being splined on the said shaft, resilient means for holding the worm against shifting and in driving relation with the said worm gear during the closing of the window and yielding to permit axial shifting of the worm along the shaft upon further turning of the worm when the window panel is closed, operative connections between the worm and the lock actuated in the shifting of the worm for throwing the lock into interengagement with the window panel when closed.

8. In a window assembly comprising a window opening and a window panel arranged to be moved to closed position, in combination an operator for moving the window to closed position, a lock for locking the window panel in closed position,

- the said window panel operator comprising an axially shiftable rotatable driving member and a rotatable driven member, operative connections between the rotatable driven member and the
- 5 window panel whereby the driven member is stationary when the window panel reaches closed position, operative connections between the shiftable rotatable driving member and the lock, the said driving member driving the driven member
- 10 during the closing of the window panel but when the driving load reaches a predetermined point, as when the panel is closed, the said driven member remains stationary and the torque reaction shifts the driving member axially and transmits
- 15 the driving force through said connections to throw said lock into locking engagement with said window panel.
9. In a window assembly comprising a window opening and a swinging window panel arranged
- 20 to be moved to open and closed positions, the combination of a window operator including a worm and a worm gear, a shaft for interconnecting the worm gear and the swinging window, a lock bolt projectable into interengaging relation
- 25 with the window panel when closed to lock the same, a shiftable member carried by the worm gear, operative connections between the said shiftable member and the latch bolt whereby

when the window reaches closed position the worm is disengaged from the worm gear and meshes with the shiftable member to shift the same and throw the latch bolt into interengagement with the closed window panel.

10. In a window assembly comprising a window opening and a swinging window panel arranged to be moved to open and closed positions, the combination of a window operator including a worm and a worm gear, a shaft for interconnecting the worm gear and the swinging window, a lock bolt projectable into interengaging relation with the window panel when closed to lock the same, a shiftable member carried by the worm gear, operative connections between the said shiftable member and the latch bolt whereby when the window reaches closed position the worm is disengaged from the worm gear and meshes with the shiftable member to shift the same and throw the latch bolt into interengagement with the closed window panel, and when the worm is turned to open the window the driving torque is transmitted through the shiftable connection to the worm gear to rotate the same into meshing driving relation with the worm to swing the window open.

JOHN B. FLYNN.
